Edward J. Simanek and Norman Flesch, Chicago,
Ill., assignors to American Steel Foundries, Chi-
cago, Ill., a corporation of New Jersey

Application October 26, 1946, Serial No. 705,892

19 Claims. (Cl. 188—56)

1

Our invention relates to brake rigging for a railway car truck, and more particularly to such an arrangement of clasp brake type wherein the power means for actuation of said brake rigging are mounted on the outboard sides of the truck frame.

One object of our invention is to design such a type of brake rigging for a six wheel truck wherein the body clearances are particularly meager, said rigging including a set of substantially vertically disposed interconnected cylinder levers positioned outboard of the frame and connected to actuating means mounted on the outboard sides of said frame.

Another object of our invention is to design such a type of brake rigging wherein a plurality of power means will be supported on each side of the truck intermediate the ends thereof, said power means on the same side of the truck being connected in tandem and actuating a unified structure of rigging on the same one side of the truck.

A further object of our invention is to provide, in the brake rigging of a railway car truck, novel release means for holding the rigging in "off position" when not actuated by the power means associated therewith, said means including a plurality of springs connected at one end to a member of the rigging and at the other end to the frame at a point adjacent the dead end of said rigging.

These and other objects of our invention will be apparent from the specification and the drawings.

In the drawings, wherein for clarity details are omitted from certain views where better shown in others;

Figures 1 and 1A are top plan views showing one-half of a truck and brake structure embodying our invention, Figure 1 showing one end thereof and Figure 1A the other end;

Figures 2 and 2A are side elevations respectively of the truck structure shown in Figures 1 and 1A;

Figure 3 is an end elevation of the structure shown in Figures 1, 1A, 2 and 2A, the view being taken from the left as seen in Figures 1 and 2;

Figure 4 is an end elevation of the structure shown in Figures 1, 1A, 2 and 2A, the view being taken from the right as seen in Figures 1A and 2A; and

Figure 5 is a sectional view of the structure shown in Figures 1 and 1A, the view being taken in the transverse vertical plane substantially as indicated by line 5—5 of Figure 1.

Describing our novel brake arrangement in greater detail, the truck structure comprises the

side members 2 integrally joined intermediate the ends of the truck by spaced transoms 4, 4, each of said members presenting adjacent their ends the column guides 6, 6 and 8, 8 and intermediate their ends the column guides 10, 10 arranged for engagement in the usual manner with journal boxes (not shown) serving as the usual means of connection to the journal portions of the wheel and axle assemblies 12, 14 and 16.

The power means (Figure 1) may consist of a pair of spaced air cylinders 18 and 20 (Figures 1 and 1A) arranged in tandem, the adjacent sides of said cylinders being secured to said side member 2 by the securing means 22, 22 and 24, 24 as at 26, 26 (Figure 2A) and 28, 28 (Figure 2) respectively.

The cylinder 18 has a piston 30 pivotally connected as at 32 (Figure 2A) to the lower end of the diagonally arranged approximately upright cylinder lever 34, the upper end of said lever projecting into the diagonal opening 36 (Figure 1A) in the bracket 38, said opening being defined by the spaced end webs 40, 40 and the spaced parallel diagonal inboard and outboard webs 42, 42 of said bracket 38, said inboard web merging with the mounting plate 44 (Figure 1A) secured to said member 2 adjacent the top thereof by the securing means 46, 46.

The upper end of said cylinder lever 34 may pivot as at 48 on the pin 50 (Figure 2A) extending through said outboard and inboard webs 42, 42 of said bracket 38. To secure the pin 50 in the bracket 38 a pair of outwardly projecting spaced lugs 52, 52 may be provided on the said outboard web 42. Aligned horizontal openings 54, 54 (Figure 1A) may be provided in said lugs 52 for reception of a cotter key (not shown) which may hold said pin 50 from falling out of position.

The cylinder lever 34 may be pivoted intermediate the ends thereof as at 54 (Figure 2A) to one end of the rod 56 (Figure 1A) passing over said cylinder 18 and lying in the longitudinal vertical plane substantially bisecting said cylinder, said rod having its opposite end pivotally connected as at 58 (Figure 1) to the cylinder lever 60 (Figure 2) intermediate the ends thereof, said cylinder lever 60 being diagonally arranged and parallel to said cylinder lever 34.

The upper end of the lever 60 may be fulcrumed as at 62 to the bracket 64, said bracket 64 being fastened to said side member 2 adjacent the top thereof by the securing means 66, 66. The construction of bracket 64 will not be described in

detail inasmuch as it is identical with bracket 38.

The lower end of the cylinder lever 60 may be pivotally connected as at 67 (Figure 2) to the piston 68 (Figure 1) of the cylinder 20.

To the cylinder lever 60 at the point 58 previously described may also be pivoted one end of the rod 70 passing over said cylinder 20 and lying in the longitudinal vertical plane substantially bisecting said cylinder 20 and lying in approximately the axial plane of the said rod 56. The other end of said rod 70 extends beyond the inturned end 72 of the side member 2 and is pivoted as at 74 to the outboard end of the horizontal dead lever 76, said dead lever being fulcrumed intermediate its ends as at 78 on the automatic slack adjuster 80 secured to said end 72 as by bolts 82, 82 (Figure 3).

The inboard end of the dead lever 76 is pivoted as at 84 to one end of the rod 86, the other end of said rod being pivotally secured as at 88 (Figure 2) to the upper end of the vertical live truck lever 90 positioned adjacent one side of the wheel and axle assembly 12, said live lever extending through the horizontal rod 92 and being pivoted and adjustably connected between its ends as at either 94 or 96 intermediate the ends of said horizontal rod. The outer end of said rod 92 may be antifrictionally supported on the roller bearing 98 mounted on the support bracket 100 (Figure 3) secured to said inturned end 72 as at 102 by the bolts 104, while the other end of said rod 92 extends over the wheel and axle assembly 12 and is pivoted as at 106 to the vertical live truck lever 108 intermediate the ends thereof, said lever 108 being disposed adjacent the opposite side of the said wheel and axle assembly 12.

The lower end of the live lever 90 may be pivotally fastened to one end of the fulcrum 110 secured as by rivets 112, 112 (Figure 3) to the brake beam 114, said beam being pivoted at the end thereof to the lower extremity of the hanger lever 116 which in turn may be pivotally hung as at 118 at its upper end from the underside of said inturned end 72. Intermediate the ends of the hanger lever 116 may pivot as at 120 the brake head and shoe assembly 122 positioned adjacent said wheel and axle assembly 12, said assembly 122 including a brake head balancing device 124.

Around the beam 114 may be looped the safety rod 126 fastened as at 128, 128 from the underside of said inturned end 72, said safety rod serving to uphold said beam should its other supports fail.

The upper end of the live truck lever 108 may be pivoted as at 129 to the adjacent jaw end of the equalizer 130 (Figure 1) extending between said members 2 and parallel to the adjacent transom 4 and slidably supported on the angles 132 carried on said adjacent transom 4 and being fastened thereto by the securing means 134 (Figure 5).

The lower end of the live truck lever 108 may be pivotally secured to the fulcrum 136 on the connector 138, the trunnion end of said connector being supported by the hanger lever 140 hung from the frame as at 142, said hanger lever 140 supporting intermediate its ends as at 144 the usual brake head 146 with the balancing device 148 and brake shoe 150.

The equalizer 130 previously described may be secured intermediate its ends at a point as at 152 (Figure 1) to one end of the pull rod 154, said rod extending through the aligned openings 156, 156 in the adjacent transom 4 and being

antifrictionally supported as at 158 by a roller provided on the bracket 160 carried by the said transom 4. The other end of the pull rod 154 may be pivoted as at 162 (Figure 2) to the upper end of the live truck lever 164, the lower end of which may be connected to the fulcrum 166 of the connector 168, the trunnion end of said connector being supported by the hanger lever 170 hung from the frame as at 172, said hanger lever 170 supporting braking means (not shown) as at 174.

A safety rod 175 may be looped under the said connectors 138 and 168, here illustrated as beams, and connected as at 177, 177 to the span bolster 180.

The pull rod 176 is connected to the live lever 164 as at 165 and extends through the aligned openings 178, 178 in the span bolster 180 positioned intermediate the transoms 4, 4 affording support therefor in the usual manner, said rod 176 being antifrictionally supported as at 182 and 184 by the rollers provided on the brackets 186 and 188 carried by said span bolster.

The opposite end of the pull rod 176 may be pivoted as at 190 (Figure 2A) to the live truck lever 192, the lower end of said lever having a pivotal connection as at 194 to the fulcrum 196 on the connector 198, the trunnion end of said connector 198 being supported by the hanger lever 200 hung from the frame as at 202 and carrying braking means (not shown) as at 204 for association with the periphery of the assembly 14 previously described.

The upper end of the live truck lever 192 may be connected through the pull rod 206 to the equalizer 208 (Figure 1A) slidably supported on the bracket 210 carried by the adjacent transom 4. The pull rod 206 may extend through the aligned openings 212, 212 in the said adjacent transom 4 and may be antifrictionally supported as at 214 by the roller bearing on the bracket 216 carried by the said transom 4.

The pivotal jaw end of the equalizer 208 may be pivotally connected to the upper end of the live truck lever 218 (Figure 2A) positioned adjacent one side of the said wheel and axle assembly 16, the lower end of said lever being connected to the fulcrum 220 of the connector 222, the trunnion end of said connector being supported by the hanger lever 224 which is hung from the truck frame as at 226 adjacent the juncture of the said last-mentioned transom 4 with the side member 2, said hanger lever carrying braking means as at 227.

The safety rod 228 may pass under the said connectors 198 and 222 and be connected as at 230, 230 on the span bolster 180.

The pull rod 232 may extend over the wheel and axle assembly 16 and may be connected to the said live lever 218 as at 234 (Figure 2A) at one end. A manually adjustable slack adjuster 236 of any suitable type is provided at the other end of said pull rod which is connected as at 237 to the dead truck lever 238 positioned at the opposite side of the said assembly 16, said dead lever 238 being pivoted at its upper extremity as at 240 to the bracket 242 secured in any convenient manner as by rivets 244, 244 to the inturned end 245 of the side member 2.

To the bracket 242 may be hooked as at 246 one end of the release spring 248, the other end of said spring being hooked to the equalizer 208 as at 250.

It may be noted that the other end of the equalizer 208 (not shown) is similarly hooked to a release spring (not shown) which is hooked

to a bracket on the other side frame (not shown) and that the axes of the two springs converge inwardly.

The lower end of the dead lever 238 may be connected to the fulcrum 252 of the beam 254, the trunnion end of said beam being supported by the hanger lever 256 hung as at 258 from the said interned end 245 of said member 2. Connected to said end as at 260, 260 is a safety support 262 for said beam 254, said support being in the form of a loop bracket.

On the hanger lever 256 as at 264 may be hung the brake means (not shown).

Operation of the brake mechanism is as follows: Assuming the brakes to be in released position, actuation of the power means or brake cylinders 18 and 20 moves the piston rods 30 and 68 to the right and causes the cylinder levers 34 and 60 to rotate simultaneously in a counterclockwise direction about their respective pivot points 48 and 62 and through the rods 56 and 70 cause the outboard end of the horizontal dead lever 76 to move to the right about the pivot 78, whereupon the inboard end of said dead lever 76 moves to the left. Movement of the dead lever 76 pulls the rod 86 to the left which in turn through the pivot point 88 actuates the live lever 90 in a counterclockwise direction and pulls it to the left and thus through the fulcrum 110 on the connector 114 brings the brake shoe assembly 122 into engagement with the periphery of the adjacent wheel and axle assembly 12.

The movement of the live lever 90 also actuates the rod 92 to the left which in turn pulls the live lever 108 to the left, and rotates it in a clockwise direction, said live lever bringing the connected brake shoe 150 into engagement with the periphery of said assembly 12.

The movement of the live lever 108 pulls the equalizer 130 to the left which in turn pulls the rod 154 to the left rotating the live lever 164 in a counterclockwise direction and also pulls it to the left, the movement of said live lever 164 urging braking means connected thereto against the periphery of the wheel and axle assembly 14.

The movement of live lever 164 in turn pulls the rod 176 to the left which rotates the live lever 192 in a clockwise direction operating a braking mechanism on the opposite side of the assembly 14 against the periphery thereof.

The movement of the lever 192 pulls the rod 206 to the left, said rod rotating the live lever 218 in a counterclockwise direction and pulling the rod 232 which rotates the dead lever 238 in a clockwise direction on the pivot 240 and actuating braking means on said levers 218 and 238, said braking means clasping the periphery of the wheel and axle assembly 16 therebetween.

Release of the power means with the aid of the release springs 248 causes the various parts to move in reverse of the directions just specified, thus releasing the brake mechanism.

It is to be understood that we do not wish to be limited by the exact embodiment of the device shown which is merely by way of illustration and not limitation as various and other forms of the device will, of course, be apparent to those skilled in the art without departing from the spirit of the invention or the scope of the claims.

We claim:

1. In a brake arrangement for a six wheel

railway car truck, a truck frame and supporting end and intermediate wheel and axle assemblies, brake means for said assemblies, brake rigging operatively connected to said brake means and comprising interconnected live truck levers at opposite sides of one of said end assemblies and said intermediate assembly, interconnected live and dead truck levers at opposite sides of the other end assembly, an equalizer connected to one of the live truck levers associated with said intermediate assembly and said second-mentioned live truck lever, brake release means connected in parallel with said second-mentioned levers, a plurality of power cylinder devices arranged in tandem and mounted on the outboard side of said frame, a substantially vertical cylinder lever pivoted to each of said devices at its lower end and to the frame at its upper end, means interconnecting said cylinder levers and an operative connection between one of said cylinder levers and the live truck lever of said one end assembly.

2. In a brake arrangement, a truck frame including a side member, supporting wheel and axle assemblies, braking means for said assemblies, a horizontal dead lever pivoted intermediate the ends thereof on said side member at a point adjacent one end of said side member and pivoted at its inner end to said braking means and operatively connected at its outer end to power means, the said power means including a pair of cylinders arranged in tandem and mounted on said member intermediate the ends thereof, a substantially upright cylinder lever pivoted at one end to said frame adjacent each cylinder and connected thereto at the other end, and horizontally positioned interconnecting means for said cylinder levers pivoted at opposite ends thereof to said cylinder levers, said interconnecting means being disposed in a substantially vertical plane bisecting said cylinders longitudinally and overlying one of said cylinders, said cylinder levers and interconnecting means being aligned with each other longitudinally of said cylinders.

3. In a brake arrangement, a truck frame including a side member, supporting wheel and axle assemblies, braking means for said assemblies, a horizontal dead lever pivoted intermediate the ends thereof on said side member at a point adjacent one end of said side member and pivoted at its inner end to said braking means and operatively connected at its outer end to power means, the said power means including a pair of cylinders arranged in tandem and mounted on said member intermediate the ends thereof, a substantially upright cylinder lever pivoted at one end to said frame adjacent each cylinder and connected thereto at the other end, and horizontally positioned interconnecting means for said cylinder levers pivoted at opposite ends thereof to said cylinder levers, said interconnecting means being disposed in a substantially vertical plane bisecting said cylinders longitudinally and overlying one of said cylinders.

4. In a brake arrangement, a truck frame including a side member, supporting wheel and axle assemblies, braking means for said assemblies, a horizontal dead lever pivoted intermediate the ends thereof on said side member at a point adjacent one end of said side member and pivoted at its inner end to said braking means and operatively connected at its outer end to power means, the said power means including a pair of cylinders arranged in tandem and mounted

on said member intermediate the ends thereof, a substantially upright cylinder lever pivoted at one end to said frame adjacent each cylinder and connected thereto at the other end, and horizontally positioned interconnecting means for said cylinder levers pivoted at opposite ends thereof to said cylinder levers, said interconnecting means being disposed in a substantially vertical plane bisecting said cylinders longitudinally.

5. In a brake arrangement, the combination of a truck frame including a side frame, wheel and axle assemblies disposed in supporting relation to said truck frame, brake rigging associated with said wheels for braking cooperation therewith, operating means for said brake rigging including a pair of horizontally disposed cylinders mounted on said side frame intermediate the ends thereof, parallel interconnected substantially upright cylinder levers fulcrumed from said side frame at their corresponding upper ends and connected at their lower ends to adjacent cylinders, a horizontally disposed dead lever pivoted from said side frame at a point adjacent one end thereof and connected at its inner end to said rigging, and a pull rod connected at one end to one of said cylinder levers and passing over the adjacent cylinder and connected at the other end to the outer end of said horizontally disposed dead lever.

6. In a brake arrangement, the combination of a truck frame including a side frame, wheel and axle assemblies disposed in supporting relation to said truck frame, brake rigging associated with said wheels for braking cooperation therewith, operating means for said brake rigging including a pair of cylinders mounted on said side frame at spaced points, a pair of levers each being pivoted to the piston of the adjacent cylinder at one end and to said frame at the other end, means interconnecting said levers, said means being pivoted to said levers at points intermediate the ends thereof, said levers being disposed in a substantially vertical plane extending longitudinally of said cylinders, and means pivoted to one of said levers at the pivot of said first-mentioned means for interconnecting said levers to said rigging.

7. In a car truck, the combination of a side frame, wheel and axle assemblies, brackets mounted on said frame adjacent the top thereof at spaced points intermediate the ends of said frame slightly inclined dead levers pivoted at their upper ends from said brackets, power means connected to the lower end of each lever, said power means being disposed horizontally and arranged in tandem and operating in the same direction, a pull rod interconnecting said levers intermediate the ends thereof and passing over one of said power means, a pull rod pivoted to one of said levers at the point of connection of said one lever to said first-mentioned pull rod and being co-axial with said first-mentioned pull rod, and braking means for said wheel and axle assemblies operatively connected to said second-mentioned pull rod.

8. In a railway car truck, a frame including a side member having inturned ends, supporting wheel and axle assemblies, braking means for said assemblies, power means for said braking means, a horizontal dead lever fulcrumed from one end of said side member adjacent the corner thereof and connected at its inner end to said braking means and at its outer end to said power means, said power means including a plu-

rality of cylinders mounted on said side member at spaced points intermediate the ends thereof, a substantially vertical dead lever fulcrumed from said side member at the upper end thereof adjacent each cylinder and connected thereto at its lower end, a connection between said last-mentioned dead levers, said connection being disposed above said cylinders and lying in a plane extending longitudinally thereof.

10. 9. In a brake arrangement, the combination of a truck frame including a side frame, wheel and axle assemblies disposed in supporting relation to said truck frame, brake rigging associated with said wheel and axle assemblies for braking cooperation therewith, operating means for said brake rigging including dual power means arranged in tandem and mounted on said side frame, said power means operating in one direction, spaced substantially vertical levers pivotally connected to said power means at one end and to said frame at the other end, a connecting rod extending between said levers and pivoted at opposite ends thereof to said levers at points intermediate the ends thereof, and means pivoted to one of said levers at the point of connection of said rod with said lever for connecting the latter to said rigging.

10. 30. In a brake arrangement, a truck frame including a side member, supporting wheel and axle assemblies, braking means for said assemblies, a horizontal dead lever pivoted intermediate the ends thereof on said side member at a point adjacent one end of said side member and pivoted at its inner end to said braking means and operatively connected at its outer end to power means, the power means including a pair of cylinders arranged in tandem and mounted on said member intermediate the ends thereof, a substantially upright cylinder lever pivoted at one end to said frame adjacent each cylinder and connected thereto at the other end, and horizontally positioned interconnecting means for said cylinder levers pivoted at opposite ends thereof to said cylinder levers.

45. 11. In a railway car truck, a truck frame, spaced supporting end and intermediate wheel and axle assemblies, brake means for said assemblies, said brake means being dead-ended at one end of said truck and including live and dead truck levers at opposite sides of the adjacent end wheel and axle assembly, brake release means operatively connected to said live truck lever and to said frame, and power means operatively connected to the live end of said brake means and including spaced power devices mounted on said frame and connected in tandem to each other.

50. 12. In a railway car truck, a truck frame including a side frame, spaced supporting wheel and axle assemblies, braking means for said assemblies, power means for said braking means, a dead lever fulcrumed from one end of said side frame and having its inner end connected to said braking means and having its outer end connected to said power means, the arrangement of said power means on said side frame comprising horizontally disposed cylinders mounted thereon in tandem and interconnected dead levers fulcrumed from said frame and connected to said cylinders, said last-mentioned dead levers being aligned with each other longitudinally of said cylinders and lying in a substantially vertical plane.

55. 13. In a brake arrangement, the combination of a truck frame including a side frame, wheel and axle assemblies disposed in supporting relation to said truck frame, brake rigging associated with

said wheel and axle assemblies for braking cooperation therewith, operating means for said brake rigging including a pair of cylinders arranged in tandem and mounted on said side frame intermediate the ends thereof, and a pair of substantially vertical cylinder levers pivoted at their upper ends to said truck frame and connected at their lower ends to the respective of said cylinders and connected intermediate their ends to each other and to said brake rigging.

14. In a railway car truck, a frame having side members, end and intermediate wheel and axle assemblies, dual power means connected in tandem on each side of said frame, said tandem connection comprising interconnected substantially vertical cylinder levers fulcrumed from the frame at their upper ends and connected at their lower ends to adjacent power means, horizontal dead levers fulcrumed from opposite corners of said frame adjacent one end thereof and operatively connected to adjacent cylinder levers, said cylinder levers on each side of said frame being aligned with each other longitudinally of said cylinders, and braking means for said assemblies operatively connected to said horizontal dead levers.

15. In a railway car truck, a side frame, supporting wheel and axle assemblies, braking means for said assemblies, a dual power means arranged in tandem and connected to each other and mounted on said frame intermediate the top and bottom thereof and operatively associated with said braking means, said connections comprising a pair of substantially upright cylinder levers hung from said frame at spaced points adjacent the top of said frame, each of said levers extending downwardly to respective of said power means and connected thereto, and a pull rod overlying one of said power means interconnecting said cylinder levers intermediate the ends thereof.

16. In a railway car truck, a truck frame member, spaced supporting wheel and axle assemblies, brake means for said assemblies, power means for said brake means including spaced substantially horizontally disposed cylinders mounted on said member in alignment with each other longitudinally of the truck and arranged to operate in the same direction, means interconnecting said cylinders including a dead lever pivoted to the frame member adjacent each cylinder and operatively connected thereto, a connection between said le-

vers, and means operatively connecting said brake means with one of said levers.

17. In a car truck, a truck frame, supporting wheel and axle assemblies, brake means for said assemblies, power means for said brake means including a plurality of power devices spaced longitudinally of the truck carried by said frame and arranged to operate in the same direction, a plurality of interconnected spaced dead levers fulcrumed to said frame and operatively connected to the respective power devices, and an operative connection between one of said levers and said brake means, said levers being arranged substantially in alignment with each other longitudinally of the truck.

18. In a railway car truck, a truck frame, spaced wheel and axle assemblies, a plurality of cylinder devices spaced longitudinally of the truck carried by said frame and arranged to operate in the same direction, a lever pivoted to said frame adjacent each of said devices and operatively connected thereto, means extending longitudinally of the truck in a plane substantially bisecting said cylinder devices longitudinally interconnecting said levers, brake means for said assemblies, and an operative connection between one of said levers and said brake means.

19. In a railway car truck, a truck member, spaced wheel and axle assemblies, brake means for said assemblies, power means for actuating said brake means including a plurality of spaced power cylinder devices carried by said member, and means interconnecting said devices with each other and with said brake means including spaced interconnected levers pivotally connected to said member and operatively connected to respective devices.
